UNITED STATES PATENT OFFICE.

FRANK TURNER, OF NEW YORK, N. Y.

MUSICAL INSTRUMENT.

Application filed October 11, 1927. Serial No. 225,432.

This invention relates to musical instruments and especially to instruments of the wind type wherein the variations in tone or pitch are produced according to the variations 5 in length of the air column or tube.

Among the objects of the invention is to provide a musical instrument with improved means whereby the effective length of the tube may be varied to any desired degree.

Another object of the invention is to provide a musical instrument of the type set forth wherein the pitch can be varied continuously, either up or down, so that the tones produced can be slurred or played without a 15 break between them.

A still further object of the invention is to provide a tone producing instrument which depends for its variations in pitch upon the variations in length of the tube, following the 20 general principle that the longer the tube the lower the tone or pitch, and one wherein the tube is a sectional object composed of a series or succession of telescopically mounted sections and with external means connected to 25 the several sections for holding them respectively in a certain predetermined relation to one another.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a side elevation of one embodiment of my improvement exemplified in some respects in the form of a clarinet, one having a mouthpiece with a reed for initiating the tones.

Fig. 2 is a view similar to Fig. 1 showing the shortened or collapsed form of the instrument.

Fig. 3 is an end elevation with the mouthpiece removed.

Figs. 4 and 5 are detail views showing variations in forms of joint structures between the telescopic tube sections and levers.

Fig. 6 is a vertical longitudinal section on the line 6—6 of Fig. 1.

Fig. 7 is an enlarged central sectional view

of a slight modification and illustrating that 55 form of the invention in which the mouthpiece is a fixture and has levers connected directly therewith.

Fig. 8 is a detail view of one of the intermediate sections of the tube structure.

Fig. 9 is a detail view of the first section of an instrument embodying the improvements but relating to the saxophone type.

Fig. 10 is a modification of my invention showing its application to that form of sound 65 producing device in which the tones are initiated at the larger end as in a whistle or flute.

Fig. 11 is a further modification showing variation in form of the lever mechanism.

Figs. 12 and 13 are still further variations 70 in lever devices.

Referring now more specifically to the drawings I show a musical or sound producing instrument comprising a succession of telescopically mounted sections A, B, and C, 75 section A being the smallest in diameter and adapted as a mouthpiece section, the section C being the largest in caliber and carrying any suitable size or design of bell formation 10, and the intermediate sections B of any 80 suitable or desired number, one or more, are substantially cylindrical in form subject to such variations as may be noted hereinafter. Each tube section bears at or adjacent to one end a collar as indicated at 11 for several reasons, among which may be noted, first, the matter of re-enforcement or strengthening thereof, taking into consideration that the tube sections are of relatively thin metal, and secondly, to constitute means for the attachment 85 of regulating devices. The tubing in all the sections may be perfectly cylindrical on the inside or in certain cases it may be tapered. In Fig. 7 the mouthpiece end of the bore is shown slightly tapered at 12 toward the 90 mouthpiece, and in Fig. 8, I show an internal flare or taper of the bore toward the next larger section as at 13. This feature is optional and is not shown on Fig. 6. It is preferred that the end of any section which telescopes within the next section shall be very 95 slightly larger in outside diameter as at 14 than the main portion of the section so as to insure suitable airtightness of fit between the two relatively movable sections without 100 excessive friction. The difference in diameter between the enlargement 14 and the rest of the tube is much exaggerated in the draw-

ing and should preferably be so small to be hardly noticeable and for this reason is not shown on any other drawings. When the instrument is closed as in Fig. 2 the ends of the sections remote from the mouthpiece, may be even, or each section may extend slightly beyond the adjacent end of the next smaller section as shown in dotted lines.

As above premised the sounds or tones may be initiated by any form of mouthpiece or blow opening and may be blown by the mouth or by mechanical means and if performed by the mouth or lips, the tones may be initiated by vibration of the lips, vibration of the reed or plurality of reeds, by the use of a blow hole as in a flute or whistle or by any other known device. In most of the illustrations I indicate a mouthpiece of the clarinet type in which a reed is clamped to the body of the mouthpiece by means of a ligature as is well understood by any instrumentalist. The mouthpiece 15 may be connected directly to the first tube A' as in Fig. 7, or it may be secured detachably to a reduced neck portion 16 as in Figs. 6 and 9. Where the mouthpiece is detachable a collar 11 is employed.

While any section of the tube is adapted for free slideable or telescopic movement with respect to the next larger section, I provide means for causing all the sections to move with respect to one another according to a predetermined rule or principle, and at the same time the mechanical connections between the several sections are calculated to stabilize and support the several sections, preventing them normally from cramping or sagging. It is contemplated, furthermore, that the connections between the several sections shall be such that the largest or most remote sections of long instruments may be controlled or manipulated as a result of the collapsing or manipulation of other sections. To this end I provide a system or assemblage of lever devices which in most of the instances partake of the nature of lazy tongs suitably pivoted to one another and to the several tubular sections. In Figs. 1, 2, and 6, these lever members consist of first and last shorter links 17 and intermediate longer links 18. The short links are pivoted directly to the first and last collars 11 of the tubular sections at their inner ends, while the longer links 18 are pivoted at their mid points to the collar 11 of the intermediate sections B. As is usual in lazy tongs connections, the outer ends of all the links are articulated to one another at 19. In some instances I provide that the links from the tubular sections outward shall all be of the same length as in Figs. 1, 2, and 6, but in other instances I provide for variations of such elements as shown in Fig. 13, for example, wherein the end links 17^a adjacent to the mouthpiece are longer than the mid links. In Fig. 7 the

mouthpiece is firmly attached in any desired manner to the tube of smallest diameter, and the levers, instead of being attached to a collar, are attached directly to the mouthpiece by means of a pivot 19' in the nature of a screw having a threaded inner end screwing into the mouthpiece. The outer portion of the pivot is preferably smooth to provide an easy bearing for the lever links. A similar pivot is provided for each collar 11 for connecting reliably the lever links thereto.

It will be noted that as the tube sections increase in diameter, the collars likewise increase in diameter, but as it is desirable to maintain the line of bearings of the levers in a plane parallel to the central axis of the tube of the instrument, the smaller collars should be provided, with projections long enough to bring them to this parallel line. These projections are shown in Fig. 4 at 20 formed upon the collars, whereas in Fig. 5 they are shown at 20^a as constituting projections or lugs from the lever links. On Fig. 5 there is a small projection 20^b on the levers on the side opposite the collar. This is for the purpose of giving a longer bearing to the pivot or screw and thus tending to keep it at right angles to the levers.

As indicated in Fig. 3 I may provide one or more braces 21 which extend around the tubular portion of the instrument and connect to opposite end portions of one or more of the links 18. The brace also connects with the collar 11^c on the opposite side from the main levers.

These brackets or braces serve to stiffen the structure and may in the case of long instruments be employed as handles for the manipulation thereof. This brace is optional and can be omitted if desired. For ordinary purposes the instrument of the type shown in the first set of figures is played by the grasping of the mouthpiece end of the instrument in one hand, holding it steadily to the mouth while with the other hand the operator grasps the remote section at or near the collar 11. To play a high note the hand is moved toward the mouth while to lower the pitch it is moved away from the mouth. It is obvious, however, that for long instruments, the manipulating hand must grasp the instrument at some intermediate section and for this purpose any of the collars except the one nearest the mouthpiece may be employed or if the instrument is fitted with braces 21, one of them may be grasped.

The detail of Fig. 9 indicates the first section A² of a jointed telescopic instrument having the characteristics of a saxophone. That is to say, provided with a considerably greater degree of taper adjacent to the mouthpiece than in the other type of instrument. The succeeding sections to be used in connection with this structure may be the same as already described. The smallest tube carry-

- ing the mouthpiece; may be cylindrical as in Fig. 6, or it may have any style or degree of taper on the inside that has been used on any tubular wind instrument in that part nearest the mouthpiece.
- Fig. 10 is similar to Fig. 1 in the lever arrangement, but this is an illustration of the adaptation of the improvement to an instrument of the whistle type. A flute may also have the mouthpiece or blow opening at the large end, but for the other instruments the preferred location of the mouthpiece is on the smaller tube, though I do not limit myself to this form of construction.
- Fig. 11 is a diagram indicative of a still further variation in jointed lever connections, the levers all extending downward from the horizontal plane of the instrument, whereas in the structures previously described, the levers extend both upward and downward, it being understood that the plane of the levers in all cases is preferably vertical for the best supporting purposes. In Fig. 12 the link connections between adjacent tubular sections are linked to one another and to the sections so that the number of links is less than in the forms already explained and which are preferred in practice for greater stability and reliability.
- Fig. 13 shows a mouthpiece attached firmly to the smallest tube and having the levers 17^a attached directly to it in a manner similar to Fig. 7. The levers or links as shown at 17^a and 18^a connecting the mouthpiece tube and the next tube are a little longer than the middle levers hence the relative motion between these tubes is greater than that between the second and third and third and fourth tubes. This variance of length of the levers can be located on any part of the instrument and if desired the relative motion of each pair of adjoining tubes can be different. The levers at the large end of the instrument are also longer than those in the middle of the instrument for the following reasons: When the tubes are fully extended to play the lowest note the instrument is capable of, the tubes will lap over only a short distance, and the large end tube will have a tendency to sag. By placing the collar to which the levers are attached some distance farther forward, the levers as shown will tend to hold the large tube in alignment with the others. However, if this lever is attached farther forward and of course lengthened to permit this, the next lever connecting with 17^a must also be slightly lengthened if the relative motion between the largest and next largest sections is to be as great as between the other sections. The collar 11^a is used to stiffen and strengthen the outer tube which protects the smaller tubes that telescope within it.
- There are various types of levers which may be used in regulating the movement of the telescoping tubes. For example the lazy-
- tongs type as shown in Figs. 1, 2, 10, and 13, and numerous variations, one of which is shown in Fig. 11. When this type of levers is used the movement of the tubes may be regulated in any desired manner and the points on the levers where the collars are attached always remain in a straight line, thus helping to keep the tubes in alignment. Another type, of which Fig. 12 is an example, will regulate the movement of the tubes, but the points of attachment to the collars have less tendency to hold themselves in a straight line and so are kept in a straight line by the tubes themselves.
- I claim:
1. The herein described musical instrument comprising a tube composed of a plurality of relatively movable telescopic sections, means to initiate a tone in one of said sections to be conveyed and modified by passing through the remaining sections, and extensible connections between the several telescopic sections to cause all the sections other than the tone producing section to have positive movement in relation both to that section and to one another according to a predetermined principle.
  2. The herein described sound producing instrument of a tubular type comprising a plurality of telescopic sections, means at one of the sections for initiating a tone therein, and a series of lever members connected to one another and to the several sections for causing all the sections to move with relation to one another in a predetermined manner for varying the length of the instrument, the sections and parts of sections having telescopic engagement with each other having at all times a substantially straight common axis while the instrument is being played.
  3. A device as set forth in claim 2 in which the several sections are provided with lateral extensions and the lever members are all mounted on the same side of the instrument and pivotally connected to said extensions.
  4. A musical instrument as set forth in claim 2 in which the means for initiating a tone is a mouthpiece attached to the smallest end and to the lever system.
  5. The herein described musical instrument comprising a series of tubular sections telescopically connected to one another and increasing gradually in diameter from one end of the instrument to the other, and a series of devices in the nature of lazy tongs interconnected to one another and to the several sections for compelling movement of all the sections relatively to one another in the same direction at the same time and to an approximately uniform extent.
  6. In a musical instrument of the class set forth, the combination of a series of telescopic tubular sections increasing in diameter relatively from one end of the instrument to the other, the several sections having

lateral extensions, and link members articulated to one another and to the lateral extensions aforesaid, said extensions being of different lengths to insure that the effective radii thereof from the axis of the instrument 5 shall be approximately equal.

17. A structure as set forth in claim 2 in which the points of connection between the levers and the tube sections are all in the 10 same straight line.

18. A structure as set forth in claim 2 in which all the connections between the lever members and the tube sections are all in the 15 same line and with the levers extending both above and below the instrument when in playing position.

19. A musical instrument as set forth in claim 2 in which the lever members specified are of the lazy tongs type.

20. The herein described sound producing instrument of a tubular type comprising a plurality of telescopic sections, means at one 25 of the sections for initiating a tone therein, and a series of lever members connected to one another and to the several sections for causing all the sections to be extended or retracted simultaneously and to a predetermined extent, all the lever members being on one side of a longitudinal plane passing 30 through the axis of the instrument, and a bracket connected to one of the levers on opposite sides of the axis and extending around the tubular portion of the instrument.

21. The herein described musical instrument comprising a series of tubular sections connected telescopically to one another, a series of lever members pivotally attached to the several tubular sections and to one another to cause the sections to move relatively 35 to one another simultaneously, and a bracket secured to one of the lever members on one side of the axis of the tubular sections and connected to one of said tubular sections on the opposite side thereof.

22. In a musical wind instrument, a series 45 of relatively movable telescopic tube sections adapted to be manually extended and contracted for varying the pitch, a mouth piece for producing a tone connected to an end 50 section, which section remains relatively stationary, the other tube sections being longitudinally slidable in relation to each other and to the mouth piece section, the sections having telescopic relation with one another 55 having a common axis which remains in a substantially straight line while the instrument is being played, and extensible connections between the several telescopic sections to cause them all to move with relation to one 60 another according to a predetermined principle, each outer section moving simultaneously with relation to the section within.

23. In a musical wind instrument, a series 65 of telescopic tube sections progressively increasing in diameter, a mouth piece connected

to a section at one end of the instrument, and levers pivotally connected to each other and to the several sections for causing all the sections to move in relation to one another according to a predetermined principle, all 70 the sections except the section to which the mouth piece is connected being longitudinally movable both with relation to each other and the mouth piece section.

14. In a tubular wind instrument, a series 75 of telescopic sections successively increasing in diameter from one end of the instrument to the other; a mouth piece connected to an end section and a plurality of tube sections longitudinally movable with relation to each 80 other and the mouthpiece section, said movement being in a substantially straight line, and a series of levers pivotally connected to each other and connected to all the telescopic sections for compelling a movement of all 85 the sections relatively to one another at the same time, so that the section in telescopic relation to the mouth piece section will have the least movement and the section most remote from the mouth piece section the greatest amount of motion with relation to the mouth piece section.

15. In a musical wind instrument, in combination, a mouth piece for producing a tone, a series of at least three telescopic tube sections 95 successively increasing in diameter, a series of levers pivotally connected to each other and to all the telescopic sections for causing them to move in relation to one another in a predetermined manner, the relative movement of the sections being always the same when the instrument is expanded or contracted to any degree, and the sections and parts of sections having telescopic relation with one another, being in coaxial alignment. 100

16. A musical wind instrument of tubular type comprising a series of telescopic sections successively increasing in diameter, a mouth piece connected to the tube section of smaller 110 diameter, which section remains relatively stationary when the instrument is played, the other telescopic sections being longitudinally slidable in a substantially straight line both with relation to the mouth piece section 115 and each other, and a series of levers pivotally connected to each other and to the several telescopic sections for compelling a simultaneous movement of all the movable sections, each outer section moving in the 120 same direction over the section within, so that the section of greatest diameter has the largest amount of movement.

17. A musical instrument as set forth in claim 2, in which the levers are pivotally connected to each other to form a lazy tongs structure and in which the points of connection between the tube sections and the lazy tongs are so placed on the lazy tongs that they 125 are always in a straight line in the plane of 130

the lazy tongs and increase or decrease in distance apart as the lazy tongs is extended or contracted.

18. In a tubular wind instrument, a series of telescopic sections successively increasing in diameter, a mouth piece connected to an end section, said end section being relatively stationary, the other sections being movable in a straight line both with relation to each other and the mouth piece section, and a series of levers pivotally connected to each other to form a lazy tongs structure, and connected to the several tube sections for compelling a simultaneous movement of all the sections relatively to each other, the extent of movement of a section varying with its distance from the mouth piece section.

19. A musical wind instrument comprising a series of telescopically related tube sections progressively increasing in diameter, a mouth piece connected with an end section thereof, and a series of levers pivotally connected together to form a lazy tongs structure, said levers being connected with the several telescopic sections to cause all the sections to be extended or retracted simultaneously and to a predetermined extent, the sections having a common axis which always remains in a substantially straight line when the instrument is played.

20. In a musical instrument, a series of telescopic tube sections successively increasing in diameter, a mouth piece connected to the section of smallest diameter, and a series of levers pivotally connected together to form a lazy tongs structure and connected to all the telescopic sections for compelling a simultaneous movement of the sections relatively to each other, each outer section sliding over the section within, the section engaging the

relatively stationary mouth piece section having the smallest amount of movement, each section of greater diameter having a larger movement so that the tube section of greatest diameter has the greatest movement.

21. A musical instrument as set forth in claim 20 in which the lazy tongs levers are connected with the telescopic tube sections at the central intersections of the lazy tongs, the lazy tongs including short end links, the end sections of the instrument connecting with the short end links, and the intermediate sections connecting the central intersections of the long levers of the lazy tongs.

22. A musical wind instrument of the class set forth comprising a series of tube sections in telescopic relation and successively increasing in diameter from one end of the instrument to the other and adapted to be extended or contracted by hand to change the pitch, a series of levers pivotally connected to form a lazy tongs structure and connected to the several tube sections at the central intersections of the lazy tongs levers, the lazy tongs structure comprising short levers at each end of the said structure connecting with the tube sections at the end of the instrument, and each intersection of the long levers of the lazy tongs connecting with an intermediate tube section, the intermediate sections connecting with the lazy tongs at the ends of the tube sections nearest the small end of the instrument.

23. A musical instrument as set forth in claim 22 in which a reed mouth piece is connected to the end tube of smallest diameter, and a sound amplifying bell with the opposite end tube of largest diameter.

In testimony whereof I affix my signature.
FRANK TURNER.
